UNITED STATES PATENT OFFICE.

GEORGE C. CLARK, OF DETROIT, MICHIGAN, ASSIGNOR TO GEORGE C. CLARK METAL LAST CO., OF MISHAWAKA, INDIANA, A CORPORATION OF INDIANA.

CENTRIFUGAL CASTING-BOX.

1,300,123.

Specification of Letters Patent.

Patented Apr. 8, 1919.

Application filed July 19, 1918. Serial No. 245,724.

To all whom it may concern:

Be it known that I, GEORGE C. CLARK, a citizen of the United States, and a resident of Detroit, in the county of Wayne and 5 State of Michigan, have invented a new and Improved Centrifugal Casting-Box, of which the following is a full, clear, and exact description.

The invention relates to a centrifugal 10 casting machine such as shown and described in the Letters Patent of the United States, Number 1,263,208, granted to me on April 16, 1918.

The object of the present invention is to 15 provide a new and improved centrifugal casting box arranged to insure the formation of cast rings or bands of high tensile strength and without danger of cracking the cast rings especially along the peripheral 20 faces thereof. Another object is to prevent undue adhesion of the molten metal to the inner surface of the casting box thus allowing ready removal of a cast ring from the box.

25 With these and other objects in view, the invention consists of certain novel features of construction as hereinafter shown and described and then specifically pointed out in the claims.

30 A practical embodiment of the invention is represented in the accompanying drawings forming a part of this specification, in which similar characters of reference indicate corresponding parts in all the views.

35 Figure 1 is a sectional side elevation of the casting box;

Fig. 2 is a sectional face view of the same on the line 2—2 of Fig. 1; and

40 Fig. 3 is a similar view of the same on the line 3—3 of Fig. 1.

The casting box in its general construction comprises a back 10, a rim 11 and a cover 12, of which the back 10 is adapted to be secured to the driven shaft to rotate 45 the box at a high speed. The rim 11 preferably extends integrally from the box 10. The cover 12 is provided with a central opening 13 for the passage of a spout which delivers the molten metal to the interior of 50 the casting box, as more fully shown and described in the patent above referred to. The cover 12 is preferably hinged at 14 to the rim 11 of the casting box to allow of swinging the cover into closed position prior to 55 pouring the metal into the casting box and

into open position after the ring is cast to allow removal of the cast ring from the casting box. Suitable locking devices, which need not further be described here, hold the cover 12 locked when in closed position. 60

The back 10 and the rim 11 have their inner faces joined by a fillet 15 to permit convenient removal of the cast ring or band from the box after the cover 12 is detached. The inner surface of the rim 11 is roughened 65 preferably by providing the said inner surface with longitudinally extending ribs or teeth 20 which extend from the front face of the rim to the fillet 15. Similar ribs or teeth 21 are formed on the inner surface 70 of the back 10 and extend from the fillet 15 radially a distance toward the center of the back, as plainly indicated in Figs. 1 and 3. The inner surface of the cover 12 is provided with radially disposed ribs 22 extending 75 from the inner face of the rim 11 to the wall of the opening 13 in the cover 12, as plainly indicated in Figs. 1 and 2. In practice, the inner ends of the ribs 21 on the back 10 terminate approximately opposite 80 the inner ends of the ribs 22. It will be noticed that by the arrangement described the ribs 20, 21 and 22 form a retaining means for the molten metal to insure firm adherence of the molten metal to the inner faces 85 of the casting box thus effectively compacting the grains of copper and other metal with a view to increase the density and cohesion of the grains and to produce a cast ring of high tensile strength. It has also 90 been found that by the use of the ribs the cast ring is not liable to crack especially along the peripheral face thereof as is the case with centrifugal casting boxes as heretofore constructed. 95

Having thus described my invention, I claim as new and desire to secure by Letters Patent:—

1. A revoluble casting box provided on its inner face with minute integral annular 100 and uninterrupted contacting and retaining means adapted to be engaged by the contacting faces of the ring formed by the molten metal poured into the box.

2. A revoluble casting box, comprising 105 a back, a rim and a removable cover provided with a central opening for the introduction of the molten metal, the inner faces of the said back, rim, and cover being provided with minute integral contacting and 110

2
retaining means for the molten metal poured into the box.

3. A revoluble casting box, comprising a back, a rim and a removable cover provided with a central opening for the introduction of the molten metal, the inner faces of the said back, rim and cover being provided with minute integral contacting and retaining ribs, of which the ribs on the rim extend approximately parallel to the axis of the casting box and the ribs on the back and cover are disposed approximately radially.

10 4. A revoluble casting box having a back, a rim, a fillet connecting the inner faces of the back and rim with each other, and integral annular and uninterrupted retaining means on the inner face of the back adjacent the said fillet.

15 5. A revoluble casting box having a back provided on its inner face with integral annular retaining means for the molten metal poured into the box.

20 6. A revoluble casting box having a back provided on its inner face with integral retaining ribs extending approximately radially relative to the axis of the casting box.

25 7. A revoluble casting box having a cover

provided at its inner face with integral annular retaining means for the molten metal poured into the box.

30 8. A revoluble casting box having a cover provided with a central opening and provided at its inner face with integral retaining ribs extending approximately radially relative to the axis of the casting box.

35 9. A revoluble casting box, comprising a back and rim, the back and rim being joined by a fillet, and the inner faces of the said rim and back being provided with minute, integral retaining means adjacent the said fillet.

40 10. A revoluble casting box, comprising a back and a rim, the back and rim being joined by a fillet, and the inner faces of the said rim and back being provided with minute, integral retaining ribs, of which the ribs of the rim extend approximately parallel to the axis of the casting box from the front edge of the rim to the said fillet and the ribs of the said back extend approximately radially from the said fillet toward the center of the back.

45 50 GEORGE C. CLARK.
